J. CLARK

TRACK LINER

Filed August 6, 1925

Inventor

John Clark
Jerry Q. Matthews

Attorney

UNITED STATES PATENT OFFICE.

JOHN CLARK, OF WALKERTON, INDIANA.

TRACK LINER.

Application filed August 6, 1925. Serial No. 48,599.

To all whom it may concern:

Be it known that I, JOHN CLARK, a citizen of the United States, residing at Walkerton, in the county of St. Joseph and State of Indiana, have invented certain new and useful Improvements in Track Liners, of which the following is a specification.

The present invention relates to track liners or jacks.

10 An object of the invention is to provide an instrument for adjusting a rail laterally.

Another object of the invention is to provide a device which can be operated to accomplish the lifting and proper positioning 15 of the track rail with a minimum of labor and effort.

Still another object is to provide a device for this purpose which shall have a movable foot, by which shifting of the rail will be 20 facilitated, and which will eliminate the necessity of providing prongs or other means on the base plate to prevent its slipping on the ballast and sliding out from under the rail.

25 A further object of the invention is to provide such a device which has a lifting rail-engaging lever which has its forward end associated with a fixed pivot.

A still further object of the invention is 30 to provide a fixed pivot for the forward end of the rail-engaging and lifting lever, in combination with a frame member or support for said pivot, the support or frame member being fixed and of wedge-shaped 35 formation for the purpose of assisting in placing the liner in operation.

Other and further objects of the invention, including the provision of a device which is an improvement on my two prior 40 patents for track liners, No. 1,513,724, dated October 28, 1924, and No. 1,515,928, dated November 18, 1924, will appear from the following description taken in connection 45 with the accompanying drawings, which illustrate, by way of example, a preferred embodiment of the present invention.

The invention includes a bed plate, an operating lever provided with a slidable foot engaging said bed plate, and having 50 pivoted to it intermediate its ends a rail-engaging and lifting lever which has its forward and lower end pivoted, said pivot being in fixed relation with said bed plate.

In the drawings:

55 Fig. 1 is a side elevation showing the

operating and lifting levers partly raised;

Fig. 2 is a top plan view of the device shown in Fig. 1;

Fig. 3 is a side elevation showing the rail lifting lever and operating lever in lowered position;

Fig. 4 is a side elevation partly broken away and partly in section, on an enlarged scale, showing the movable foot of the operating lever slidably associated with the base 65 plate.

Fig. 5 is a sectional elevation of a modified form wedge member.

Referring in detail to the drawings, the reference numeral 11 indicates a base or bed 70 plate which is provided at one end with foot guiding and retaining members 12 and 13, which, in the form herein illustrated, are shown as being flat metallic plates secured by bolts 14 or other suitable means to the base plate and arranged to overlap and guide the movable foot 16 of the operating lever. Stop bolts 17 may be provided at the limits of the forward and rearward movement of the sliding foot 16 in order to 80 limit it in its extreme positions.

The slidable foot 16 is pivoted by a bolt 19 or other suitable means to the lower end of the operating lever 20, which is herein shown as having its upper end 21 formed as a socket for the reception of a lifting bar 23, which may be inserted in the socket for the purpose of providing a longer handle and thus increasing the effective lever length.

90 Pivotedly associated with the operating lever 20 is one end of a rail-engaging lever 18, which is herein shown as consisting of two spaced rail-engaging plates pivoted to the operating lever 20 by a through bolt 24 95 or other suitable means.

The forward and lower ends of the rail-engaging plates forming the rail lifting lever are pivotally associated with the base plate by a pivot bolt 26 or other suitable means 100 fixedly associated with said base plate preferably by means of an integral wedge-shaped member 27, through which said pivot bolt 26 passes. The wedge-shaped member 27 may be made separately as shown in Fig. 5, and may be secured to said base plate in fixed position by means of securing bolts 30, or by rivets or any other suitable means operable to secure said pivot bolt 26 in 105 fixed relation with said base plate.

In operation, the device is advanced to the rail to be raised and is shoved under the rail, the operating lever 20 then being raised to lift one end of the track-engaging lever 18, thereby causing it to engage with and lift the rail to be moved. As the operating lever 20 is raised, the sliding foot 16, which occupied a forward position on the base plate when the operating lever was in lowered position, slides on the base plate moving rearwardly during the lifting operation. The forward and lower end of the rail-engaging lever, however, though it turns about the pivot bolt 26, remains in fixed relation to the base plate and moves neither forwardly nor rearwardly thereon. When the rail has been moved, the operating lever is lowered, the lifted end of the rail-engaging lever being lowered with it and the sliding foot moving forwardly on the base plate. The wedge-shaped member 27 aids materially in facilitating putting the liner in position for operation, and its larger end forms the bearing for the pivot bolt 26.

What is claimed is:

1. A track liner including a base plate, an operating lever, a movable foot for said operating lever longitudinally slidable on

said base plate, said operating lever being pivotally associated with said movable foot, a track-engaging lever pivoted to said operating lever, a pivot for the forward end of said track-engaging lever, and means securing said pivot in fixed relation to said base plate, said means fixing said pivot forcing said movable foot to slide longitudinally on said base plate upon any raising or lowering movement of said operating lever and compelling all sliding movement within said track liner to take place between said movable foot and said base plate.

2. A track liner including a base plate, an operating lever, a movable foot for said operating lever longitudinally slidable on said base plate, said operating lever being pivoted to said movable foot, a track-engaging lever pivoted to said operating lever, a pivot for the forward end of said track-engaging lever, and means including a wedge-shaped member for securing said pivot to said base plate, said wedge-shaped member, by securing said pivot to said base plate, compelling all sliding movement within said track liner to take place between said movable foot and said base plate.

In testimony whereof I affix my signature.

JOHN CLARK.
